UNITED STATES PATENT OFFICE.

JOHANNES TH. PEDERSEN, OF WOODSIDE, NEW YORK.

PACKAGE-WRAPPING MACHINE.

SPECIFICATION forming part of Letters Patent No. 694,026, dated February 25, 1902.

Application filed February 25, 1901. Serial No. 48,641. (No model.)

To all whom it may concern:

Be it known that I, JOHANNES TH. PEDERSEN, a citizen of the United States, residing at Woodside, in the county of Queens and 5 State of New York, have invented an Improvement in Package-Wrapping Machines, of which the following is a specification.

My invention relates to the class of machines adapted for automatically wrapping 10 articles of merchandise of predetermined regular forms with an envelop of paper or suitable material folded around the same; and the object of my invention is to simplify 15 the construction and make more positive and expeditious the several operations of such machines.

In carrying out my invention the articles to be wrapped are fed progressively along a chute and are delivered one at a time upon a 20 moving strip of paper and therewith upon a vertically-movable platform, and I employ single-acting folders and tuckers, and folders in vertically and horizontally moving pairs for lapping the edges of the wrapping-paper, 25 forming the double end folds and upturning the folded ends and so completing the envelop and delivering the wrapped articles, and mechanism for progressively actuating such devices, all of which are hereinafter 30 more particularly set forth.

In the drawings, Figure 1 is a side elevation representing my improvement. Fig. 2 is an elevation at one end of the machine. Fig. 3 is a vertical section and partial elevation 35 at the line $x-x$ of Fig. 1. Fig. 4 is a vertical section and partial elevation at the line $y-y$ of Fig. 1. Fig. 5 is a plan of the bracket-frame and devices thereon below the chute. Fig. 6 is a cross-section through the devices 40 of Fig. 5. Fig. 7 is a longitudinal section through the lower end of the chute, through the bracket-frame, and through the vertically-movable platform and adjacent parts in the 45 position of the parts when an article to be wrapped is delivered upon the paper. Fig. 8 is a section through similar parts, but in the position where another article to be wrapped is received by an oscillating hopper at the lower end of the chute. Fig. 9 is a 50 vertical section and partial elevation through similar parts, but more at one side of the machine. Fig. 10 is a sectional plan below

the bed-plate of the parts shown in Fig. 9. Fig. 11 is a sectional plan at $z-z$ of Fig. 1 through the pedestal. Figs. 12, 13, 14, 15, 16, 55 and 17 are sections and partial elevations illustrating progressive movements of the parts producing the folded condition of the wrapper shown in Fig. 18. Fig. 19 is a cross-section in which the tuckers have been 60 brought down to make the next fold, which is shown in Fig. 20. Fig. 21 shows the next position of the parts for producing the fold of the package shown in Fig. 22. Fig. 23 shows the next position of the parts for producing the last or finished fold of the package as shown in Fig. 24. Fig. 25 illustrates 65 the package as being passed out of the machine and delivered. Fig. 26 is an elevation of the cam and adjacent parts for moving the article to be wrapped forward. Fig. 27 is an elevation of the cam and devices for disengaging the parts when no articles are being operated upon. Fig. 28 is an elevation of the cam for the paper-feed and for 70 moving the paper-feed and top-folder. Fig. 29 is an elevation of the cam for making the downward folds and raising and lowering the platform. Fig. 30 is an elevation of the cam for making the side folds, and Fig. 31 is an 75 elevation of the cam for operating the knife and severing the paper. Fig. 32 illustrates a modified construction of the platform and operating devices therefor. Fig. 33 is a partial section and elevation of the reverse side of the 80 parts shown in Fig. 26 and with the parts in the same position. Fig. 34 is a similar view, but with the parts in a different position, as hereinafter set forth. Fig. 35 is an outer edge view of the arm, Figs. 33 and 34. Fig. 36 is an inner edge view of the said arm. Fig. 90 37 is a right-hand edge elevation of the collar shown in Fig. 34, and Fig. 38 is an inverted plan of said collar.

Upon a base A, I secure standards B B and 95 C, and to the same base A, I secure a pedestal D, from the upper end of which there extends a bracket-frame D' in one direction, the said bracket-frame having an extension for the purpose of supporting the spool of 100 paper E. The said pedestal D is also provided with a delivery-chute D², having side guides, and adjacent to the upper end of the delivery-chute there is an opening through

the pedestal for the discharge of the wrapped articles which pass down the delivery-chute D² into a suitable receptacle.

The main shaft a is supported in bearings 5 upon bracket extensions of the standards B B, and on one end of said main shaft is a hand-wheel a' and on the opposite end a power-wheel a². The said main shaft also carries a small gear c, which meshes with the 10 large gear d on the cam-shaft b, and the said cam-shaft b is supported in bearings upon the said standards B B, the said large gear d being loose upon the cam-shaft b, as is also the cam e, which is made fast to the large gear 15 d, the movement as between the gear d and cam e being communicated to the shaft by means of devices hereinafter more particularly described. The cam-shaft b also carries cams e', e², e³, and e⁴. A rocker-arm f is 20 pivoted to the standard B and is provided with a roller bearing upon the cam e, and a spring f' is connected at one end to the rocker-arm f and at the other end to a short post fixed to the base A, the office of the spring f' 25 being to hold the roller of the rocker-arm f against the said cam. The arm g is pivoted to the standard B nearest to the large gear and said arm is provided with a bent lower end, and I employ a spring g', one end of 30 which is connected to the said arm and the other end to the same post to which the spring f' is connected, said spring g' tending to press the bent lower end of the arm g against the surface of a collar t, hereinafter described.

35 A rocker-arm h, having a roller in the groove of the cam e', is pivoted to the base of the standard B in line with the pivot of the rocker-arm f, and this rocker-arm h carries a slotted frame h', the office of which is to move 40 the top-folder 7 in one direction and to form a guide for parts hereinafter described. The rod 36 of the top-folder 7 has a fixed adjustable collar h² adjacent to the frame h', against which the frame bears.

45 i i' are companion rocker-arms pivoted to the standard C and each carrying a roller moving in grooves in the large cam e², which cam imparts to said rocker-arms vertical or up-and-down movements, the free ends of 50 said rocker-arms passing into slotted frames connected to operating parts hereinafter described.

An arm k is connected to a shaft 45, in bearings on the pedestal D, and the free end of 55 said arm is provided with a roller moving in the slot of the cam e³ for effecting the operation of parts hereinafter described. A rocker-arm l is pivoted at one end to a bearing of the standard C, and said rocker-arm is 60 carries a roller moving in the groove of the cam e⁴, and the free end of said rocker-arm is pivotally connected to a link 2, in turn connected to the knife 1, the up-and-down movement imparted to said rocker-arm serving the 65 purpose of operating the said knife so as to sever the paper into portions of the desired

size for wrapping the article passing through the machine.

A rod m is pivoted to the rocker-arm f and slides through parts of the bracket-frame D', 70 and a rod n, pivoted to the rocker-arm h, also slides through parts of the said bracket-frame, and I provide a spring m' on the rod m, between adjustable heads, for applying a yielding tension to the said rod m and the parts 75 connected therewith.

The chute o occupies an inclined position, and pivoted to the lower end of the said chute is an oscillating hopper o', provided with hook-ended arms 3. An arm 16, secured to 80 the bracket-frame D' and to which the said chute is pivotally connected, carries a cross-bar 17, adjustably secured thereto, and an arm 18 is pivoted to the chute and comes between the lower end of the chute and the upper surface of the cross-bar, so that the chute is supported by its pivotal connection to the arm 16 and by resting upon the arm 18 and the cross-bar 17. This arm 18 is provided with an upturned end passing up between 85 the sides of the chute into the path of articles coming down the chute, and said arm is provided with a hook end 19. (See especially Figs. 7 and 8.)

A slide-frame 4, carrying a roller 5, is connected by an arm 21 to the rod m, so that with the longitudinal movement of the rod m by the rocker-arm f the said slide-frame and roller are moved back and forth over the surface of the plate 10, which plate has a vertical 95 open portion through which the article to be wrapped is caused to pass, and I provide, pivotally connected to the chute, a gravity-roller 20, (see Figs. 1 and 7,) the office of which is to prevent the articles coming down the chute 105 becoming displaced.

I provide a vertically-movable platform 8, with a bracket extension 9, having two upright portions forming guides, and a slide-block 6 is adapted to move over the surface 110 of the said platform and bracket extension, and said slide-block is provided with a rod 38, passing through openings in the upright portions of the said bracket extensions which form guides therefor, and connected by a set-screw, and fixed to the said rod 38 is a bent arm 47, with the longer part placed substantially vertical and having a tapering lower end. A roller 48 on the large cam e² acts periodically against the lower end of the arm 47 120 to move the same, the rod 38, and the slide-block 6 in a forward direction when the platform 8 is at its lowest point, so as to force out the wrapped article, and a helical spring (see Fig. 7) of short length is preferably provided 125 around the rod 38 and against the said slide-block, acting as a cushion between the slide-block and the first of the uprights of the bracket extension 9. I provide a top-folder 130 7 having a hollow upper surface, and a rod 36 is connected to said top-folder, and it extends through openings in the uprights of the

bracket extension 9, which form guides therefor. A spring 37, secured to the upper surface of the first of said uprights, bears at its free end upon the upper surface of the said 5 top-folder, exerting a pressure to hold the same down against the slide-block 6.

The bed-plate *r* rests upon the bracket-frame *D'*, in grooves in the inner surface thereof, so that the surfaces of the bed-plate and 10 the said bracket-frame are in the same plane, (see Fig. 6,) and the said bed-plate is made with parallel depending ribs forming guides for the slide-block 11, and upon one end of the said slide-block is a roller 12, and this 15 slide-block is horizontally slotted, and a guide-pin 24 passes through the said slot and through the depending ribs of the bed-plate *r*, the said slide-block lying closely adjacent to the under surface of the said bed-plate *r*. Said bed-plate *r* has connected to its upper surface guides 25 for the paper, which passes beneath the same over the surface of the bed-plate *r*, and upon the said guides 25 are bearings 26 20 for the shaft of the upper feed-roll 27, the pivoted plate 10 having trunnions also connecting the same to the said shaft of the feed-roller outside of the bearings 26.

The under feed-roller 30 is pivoted in a yoke-frame 31, the said yoke-frame in turn 30 being pivotally connected to the guide-pin 24, and I provide one of the depending ribs from the bed-plate *r* with a bracket-arm 28, extending across beneath the slide-block 11. To this bracket-arm 28 is secured a spring 29, and an 35 adjusting-screw 32 (see Figs. 7 and 10) rests in the forked end of the spring 29 and screws through the end of the yoke-frame 31, the spring performing the office of holding the under feed-roller 30 against the upper feed-roller 40 27, the tension being regulated by the said adjusting-screw 32. I provide an arm 22, (see Figs. 1, 7, 9, and 10,) that is of offset form, with a hub surrounding the rod *n* and adjustably secured thereto by a set-screw. The free 45 end of said arm 22 is forked and receives a pin 23, extending downward from the slide-plate 11, and with the movement of the rod *n* by the rocker-arm *h* the slide-plate 11 and the roller 12 receive a longitudinal forward 50 and backward movement by means of this arm 22.

A ratchet 33, normally held by the retaining-pawl, Fig. 9; is secured upon one end of the under feed-roller 30, and a rack 34 is pivoted to the arm 22, and a spring 35, also secured to the arm 22, bears at its free end upon the under side of the rack 34, tending to keep the teeth of the rack in mesh with the teeth of the ratchet 33. From this it will be noticed 55 that when the arm 22 and the rod *n* are moving toward the right hand the teeth of the rack 34 will slip past the teeth of the ratchet 33 because of the spring action, and no movement will be imparted to the feed-rollers, but 60 when the rod *n* and the arm 22 are moving to the left the teeth of the rack 34 will engage the teeth of the ratchet 33 and turn the un-

der feed-roller and impart to the paper passing between the two feed-rollers a forward movement toward the vertically-moving platform 8 and the parts adjacent thereto.

In the position of the parts shown in Figs. 7, 9, and 10 it will be noticed that the arm 22 comes between the under surface of one of the depending ribs of the bed-plate *r* and the upper surface of a slight projection formed upon, or integral therewith, the spring 29. The projection has a cam function, and this position tends to force the spring 29 downward to release and permit the yoke-frame 31 75 to slightly descend by gravity, so as to separate the contacting surfaces of the upper and lower feed-rollers, and that as soon as the arm 22 moves to the right it moves off the projection and permits the spring 29 to return to a normal position, bringing the surface of the feed-rollers together and frictionally holding the same with the paper between them, while the rack 34 moves over the surface of the ratchet 33, and that as the 80 parts return to the left hand the rack turns the ratchet and the lower feed-roller, and feeds the paper. The parts remain in the same position until the said arm 22 again rides over the slight projection and releases 85 the pressure between the rollers and stops the feed of the paper. These parts are so timed that the desired quantity of paper is fed with the movement—that is to say, sufficient paper to cover the article to be wrapped. 100

I employ a pair of tuckers 13 in the form of rectangular plates of metal secured to depending spring-arms, the lower ends of which are secured to a cross-head 42, and to this cross-head a vertical movement is imparted 105 by means of the rocker-arm *i*, the free end of which rocker-arm engages a mortise in a frame forming part of the said cross-head, and the said cross-head is connected to a tube 40, which slides upon and outside of a tube *s*, the 110 tube *s* passing down into the pedestal *D* and being securely connected thereto in any desired manner. The arms of the said tuckers are provided with cam projections 43, and the upright portions of the pedestal are slotted 115 to receive adjustable pins 44, and with the downward movement of the cross-head 42 and the tube 40, by means of the rocker-arm *i*, the said tuckers are drawn down, and as their cam projections strike upon the pins 120 44 the said tuckers are pressed toward one another and against the surfaces of the article to be wrapped by paper.

The vertically-movable platform 8 is provided with a slotted frame 41, and the rod 39 125 is secured to the under side of the said vertically-movable platform, the said rod passing downward into the tube *s*, which forms a guide for the said rod, and the free end of the rocker-arm *i* is received in the slotted 130 frame 41, so that with the up-and-down movement of the said rocker-arm *i* the vertically-movable platform 8, its bracket extension 9, the parts connected therewith, and the rod

39 are given a vertical movement, the tube *s* serving as a guide, as hereinbefore stated, to keep said parts in vertical line.

14 represents end side folders in pairs at 5 either side of the machine. These folders are connected to rods extending downward and passing through the shafts 45, that have their bearings in the pedestal *D*. (See especially Figs. 11 and 1.) The shafts 45 are provided 10 with end screws bearing against the rods of the said folders, and while the said rods are movable vertically through the said shafts the said end screws fix their location. The said shafts 45 are connected by toggle-bars 46, and they 15 are operated by the arm *k*, extending from the end of one shaft, with the free end of the said arm and the roller thereon operatively connected with the cam *e*, the said cam imparting a swinging movement to the said arm 20 and through the same a swinging movement to the pairs of end side-folders. The end-folders 15 (see especially Figs. 1, 3, 4, 19, and 21) are in the form of spring-blades with overturned free ends, the lower ends of said folder-blades being connected upon opposite faces 25 of the pedestal *D* by screws. (Shown in Figs. 1, 3, and 4.) These end-folders are slotted for the vertical movement of the cross-head 42.

The collar *t*, hereinbefore referred to, is securely fixed to the cam-shaft *b*. This collar is preferably made of a block of metal of irregular form, as hereinafter described, with a side plate riveted thereto. (See Figs. 37 and 38.) One face of this collar is shown in 35 full lines in Fig. 27 and in dotted lines in Fig. 26, and the reverse side is shown in Figs. 33 and 34. In Figs. 26, 27, 33, and 34 the relation of the collar and the parts connected therewith to the cam *e* is clearly illustrated.

40 The periphery of this collar is of irregular outline, and in a recessed portion or groove 57 thereof a dog 49 is connected by a pivot-pin 50 to the said collar, and a spring is provided and located in a recess in the under 45 surface of the dog and the face of the collar and shown by dotted lines, the spring acting to press the dog outward. This collar is also provided with a projection 51 and a side projection 53 and central projection 55, and the 50 lower bent end of the arm *g* is provided with a stop-face 52, a projection 54, and a free end 55. The projection 53 of the collar is adapted to come against the projection 54 of the arm *g* and the projection 51 of the collar *t* against 55 the stop-face 52 of the arm *g*, the parts meeting and stopping practically simultaneously and forming a duplicate locking device with reference to the collar *t*, and from Fig. 26 it will be noticed that the cam *e* is provided 60 with a recess in the opposite face, (shown by a heavy dotted line,) said recess having a tooth 56 and receiving the larger part of the collar *t* within the recess.

In the position of the respective parts shown 65 in Fig. 27 it will be noticed that the free end of the arm *g* is in the cut-away portion 57 of the collar *t*, in contact with the back periph-

eral surface, and that the dog 49 is held within the peripheral limits of the collar by coming in contact with the surface of the arm *g*, so that the dog 49 is held out of the path of the tooth 56 of the cam *e*. The devices, Figs. 26 and 27, act in the capacity of a clutch, the office of the dog 49 being to engage the tooth 56 of the cam *e* as the cam revolves in the direction of the arrow and in the position of the dog in which the same is released so as to be projected by the spring, the cam then bearing upon the dog, as in the position Fig. 34, turns the collar *t* and with it the cam-shaft 80 *b* setting the parts in operation, the parts being set in motion only when articles are passing through the machine and being wrapped, as by reference to Fig. 2, it will be noticed that the arm 47, that is moved in one direction 85 by the roller 48, acts upon its backward movement upon the bent upper end of the arm *g* to swing said arm on the pivot connecting the same to the standard *B*, which movement draws the lower bent end of the arm away 90 from the collar to free the dog, (see Fig. 34,) whereas when no articles are passing through the machine the spring *g*' holds the lower end of the arm against the collar and confines the position of the dog, so that it cannot engage 95 the tooth of the cam, and the cam and the large gear turn around the collar free and unimpeded. (See Figs. 26, 27, and 33.)

Figs. 12 to 25, inclusive, show the various stages in the operation of the machine. In Fig. 12 the paper is shown as advanced beyond the end of the guide and over the tuckers. In Fig. 13 the tuckers have been raised and have carried up the free end of the paper outside of and parallel with the upturned 105 end of the plate 10, in which position the paper is held. Fig. 14 illustrates the articles to be wrapped, as upon the paper surface and against the bent end of the paper. Fig. 15 shows the slide-frame 4 and the roller 5 as 110 having been advanced against the article and as having forced the article to be wrapped through the opening in the plate 10 and upon the vertically-moving platform 8, the operation of the slide-frame 4, as hereinbefore 115 stated, being effected through the arm 21, the rod *m*, and the rocker-arm *f*. It will be noticed from Fig. 15 that this slide-frame 4 in pushing the article with the paper over the platform bends the free end of the paper 120 under the top-folder 7 and causes the slide-block 6 to be moved back from its position over the platform, and while the parts in this figure are shown as slightly separated they are in practice closely in contact. Between 125 the positions Fig. 15 and Fig. 16 the platform has been drawn down by the rocker-arm *i*, and the pivoted plate 11 and roller 12 have been moved forward by the arm 22 and the rod *n*, and simultaneously with said movement the knife 1 has severed the strip of paper and the roller 12 has folded the paper adjacent to the severed edge over the article, simultaneously pushing the top-folder rear-

ward out of the way, the full movement being illustrated in Fig. 17, in which the folded paper is given the form shown in Fig. 18, with the article located centrally of the folded body 5 of paper.

While the parts are held in the position Fig. 17, the tuckers 13 are moved down by the cross-head 42 and the rocker-arm *i* and are moved in and held by their cam projections 43 coming against the pins 44, the tuckers creasing in the folded paper at the respective ends of the article making the fold, as shown in Fig. 20, the next position being shown in Fig. 21, where the end side-folders 14 have 15 been set in movement by the arm *k* and the toggle-bars 46 and inturn the sides of the paper at the respective ends of the package, the folded form being represented in Fig. 22.

Between the position Fig. 19 and the position Fig. 21 the slide-plate 11 and roller 12 have 20 been returned to a normal position and the top-folder moved over the package. From the position Fig. 21 the platform 8 with its bracket extension 9 and the parts connected therewith have been moved down by the rocker-arm *i*, and the ends of the paper have been 25 upturned by being passed forcibly between the end-folders 15, which give a final wrapped form, as shown in Fig. 24, to the package. 30 The limit of movement imparted to the platform 8 brings the same approximately on a level with the opening through the pedestal D, adjacent to the delivery-chute D², and at this place the slide-block 6 is moved forward 35 by means of the arm 47, acted upon by the roller 48 on the cam *e*², forcing the package through the opening and delivering the same upon the chute, the operations thus being completed and the respective parts returning 40 to a normal position in which, with the backward movement of the rod *n* and the arm 22, the rack 34 acts upon the ratchet 33 to feed forward the paper preparatory to repeating the operations. In this return movement the slide-block 6 remains in the position Fig. 25, and the same is moved back by 45 the entrance of another article to be wrapped. (See Fig. 15.)

By reference to Figs. 7 and 8 the different 50 positions of the chute *o* will be apparent. In Fig. 8 the oscillating hopper *o'* is in a position to receive an article coming down the chute, an edge of the hopper *o'* resting upon the hook end 19 and the hook-ended arm 3 being in contact with the projection or pin *c'* upon the slide-frame 4. The chute *o* between the action of these two parts is elevated, so 55 that the upturned end of the arm 18 is out of the path of the chute and does not impede the downward movement of the articles therein. The movement of this oscillating hopper *o'* is controlled by the back-and-forth movement of the slide-frame 4, and it will 60 be apparent that from the position Fig. 8 as the slide-frame moves to the left the said hopper and chute are lowered with the retreat of the slide-frame, so that the upturned

end of the arm 18 again comes between the article in the hopper and the first article in the chute, the hook end 19 tending to elevate 70 and to tip forward the oscillating hopper upon its pivotal connection with the chute and to finally turn the said hopper when its center of gravity passes the pivot, as loaded with the article to be wrapped, so that the 75 hopper is completely overturned into the position Fig. 7, delivering one article at a time, to be wrapped upon the paper as the same is fed forward. It will be also noticed that the 80 said oscillating hopper *o'* is provided with a hook end *o*², engaged by the pivot-pin of the roller 5 as the slide-frame 4 is moved forward, the action being to return the overturned hopper from the position Fig. 7 to the position Fig. 8, the first part of the movement being effected by the pin of the roller 5 and the second part of the movement by the pin *c'* of the slide-frame 4. 85

While my improvement is adapted for wrapping various articles of merchandise of 90 predetermined regular forms, the same is especially devised and adapted for wrapping caramels and articles of similar form or character, the paper therefore being treated with paraffin; but I do not limit myself to that particular use of the machine.

The collar *t*, arm *g*, and dog 49 may be dispensed with and the large gear *d* secured directly to the cam-shaft *b*, if desired; but in such instance the disadvantage would be that 100 the entire mechanism would run continuously and feed and waste paper if no articles were being fed into the machine.

The modification, Fig. 32, serves to show that the platform 8 and its bracket extension 105 9 may be rigidly connected to or form a part of the rocker-arm *i*, in which case the standard C is higher, so that the pivotal connection of the rocker-arm *i* thereto is at such height that such arm occupies a horizontal position, and in this modification I provide a vertically-adjustable plate 58, on the lower end of which is the roller to be received in the groove of the cam *e*², the said plate being securely held to the rocker-arm *i* and the cam 110 serving to raise and lower the said arm with the platform in the same manner as shown and described hereinbefore. In this case, however, the lower position of the platform, bracket-arm, and rocker-arm will be inclined 115 when the end of the platform is brought down to deliver the wrapped article upon the discharge-chute, as shown by dotted lines in Fig. 32.

It is apparent that the parts may be duplicated and so arranged side by side in series that continuations of certain parts can be employed to operate the duplicate parts by the same cams and power devices.

I do not herein limit myself to the precise 120 mechanical devices or arrangement of parts, as deviations therefrom or equivalent modifications thereof may be employed for performing the same functions.

I claim as my invention—

1. In a package-wrapping machine and in combination, a receiving-hopper, devices for successively feeding and delivering an article at a time upon a movable strip of paper, devices for moving the article along and means for simultaneously folding the free end of the paper around one side of the article and holding the paper in position, means for severing the paper, and devices for folding the freed edge of the paper over the article and lapping the edge upon the first fold, tuckers, end side-folders and end-folders in pairs for progressively folding the paper at the ends and for forming the double end folds and upturning the folded ends to complete the envelop, and devices for delivering the wrapped articles, substantially as set forth.

2. In a package-wrapping machine, the combination with a pivoted chute, of an oscillating hopper pivoted to the chute devices for imparting a forward-and-backward swinging motion to the said hopper adapting the same to receive an article at a time from the chute and to deliver the same and a device acting in connection with the chute for arresting the movement of the articles in the chute during the movement of the hopper, substantially as set forth.

3. In a package-wrapping machine, the combination with a chute and an arm to which the same is pivotally connected, of a cross-bar adjustably connected to the said arm, an oscillating hopper pivoted to the lower end of the chute, a device pivoted to the hopper and located between the hopper and the cross-bar and performing the functions of turning the oscillating hopper in one direction and simultaneously arresting the downward movement of articles in the chute while an article is being delivered from the hopper, and means for returning the oscillating hopper to its normal position and simultaneously moving the said device out of the path of the articles so that the hopper is again filled and the operations repeated, substantially as set forth.

4. In a package-wrapping machine, the combination with a chute and an arm to which the same is pivotally connected, of a cross-bar adjustably connected to the said arm, an oscillating hopper pivoted to the lower end of the chute, a device pivoted to the hopper and located between the hopper and the cross-bar and performing the twofold function of turning the oscillating hopper in one direction and simultaneously arresting the downward movement of articles in the chute while an article is being delivered from the hopper, and means for returning the oscillating hopper to its normal position and simultaneously moving the said device out of the path of the articles so that the hopper is again filled and the operations repeated, and a pivoted gravity-roller acting above the chute to insure the proper movements of the articles passing down the chute, substantially as set forth.

5. In a package-wrapping machine, the

combination with a chute and an arm to which the same is pivotally connected, of a cross-bar adjustably connected to the said arm, an oscillating hopper pivoted to the lower end of the chute, a device pivoted to the hopper and located between the hopper and the cross-bar and performing the twofold function of turning the oscillating hopper in one direction and simultaneously arresting the downward movement of articles in the chute while an article is being delivered from the hopper, and means for returning the oscillating hopper to its normal position and simultaneously moving the said device out of the path of the articles so that the hopper is again filled and the operations repeated, and a longitudinally-movable device having two projections and performing the twofold function of advancing the article delivered by the hopper, returning the hopper to a normal position and simultaneously elevating the hopper and chute to permit of the downward movement of the articles in the chute, and the delivery of one article at a time into the hopper, substantially as set forth.

6. In a package-wrapping machine, the combination with the bed-plate and the pedestal supporting the same and parallel depending ribs from the bed-plate forming guides, of a guide for the paper upon the bed-plate, an upper feed-roller in suitable bearings therefor, a yoke-frame pivoted to the bed-plate and an under feed-roller pivoted in the yoke-frame and a spring and adjusting-screw for applying pressure and for regulating the tension of contact between the surfaces, substantially as set forth.

7. In a package-wrapping machine, the combination with the bed-plate and the pedestal supporting the same and parallel depending ribs from the bed-plate forming guides, of a guide for the paper upon the bed-plate, an upper feed-roller in bearings connected therewith, a yoke-frame pivoted to the bed-plate, and an under feed-roller pivoted in the yoke-frame, and spring-actuating devices for applying pressure and for regulating the tension of contact between the surfaces of the feed-rollers, and longitudinally-movable devices acting periodically to overcome the action of the spring and permit the yoke-frame to descend to separate the surface of the feed-rollers, substantially as set forth.

8. In a package-wrapping machine, the combination with the bed-plate and the pedestal supporting the same and parallel depending ribs from the bed-plate forming guides, of a guide for the paper upon the bed-plate, an upper feed-roller in bearings connected therewith, a yoke-frame pivoted to the bed-plate, and an under feed-roller pivoted in the yoke-frame and a spring and adjusting-screw for applying pressure and for regulating the tension of contact between the surfaces, an offset arm, a longitudinally-movable rod to which the said arm is connected, and

devices for moving the said rod and arm, the arm being adapted to depress the spring to release the tension thereof and cause the yoke-frame to descend and separate the rollers, a ratchet upon one end of the lower feed-roller, a spring-actuated rack pivoted to said arm and adapted with the movement in one direction to rotate the lower feed-roller at a time when the rollers bear frictionally in contact with one another so as to feed the paper forward, substantially as set forth.

9. In a package - wrapping machine, the combination with a vertically-movable platform, a slide-block, a top-folder and means for actuating the same, of means for delivering an article at a time upon a strip of paper and for periodically feeding forward such strip of paper, a slide-frame and roller, an arm and a horizontally-actuated rod for imparting a back-and-forth movement to the slide-frame and roller to force the article to be wrapped out upon the vertically-moving platform and simultaneously moving the slide-block out of the way, a slide-plate and roller, an arm and horizontally-actuated rod connected therewith for imparting a back-and-forth movement to the said slide-plate and roller for completing the first fold of the paper around the article and a knife and means for operating the same for simultaneously severing the strip of paper, substantially as set forth.

10. In a package - wrapping machine, the combination with a vertically-movable platform, a slide-block, a top-folder and means for actuating the same, of means for delivering an article at a time upon a strip of paper and for periodically feeding forward such strip of paper, a slide-frame and roller, an arm and a horizontally-actuated rod for imparting a back-and-forth movement to the slide-frame and roller to force the article to be wrapped out upon the vertically-movable platform and simultaneously moving the slide-block out of the way, a slide-plate and roller, an arm and horizontally-actuated rod connected therewith for imparting a back-and-forth movement to the said slide-plate and roller for completing the first fold of the paper around the article, and a knife and means for operating the same for severing the strip of paper, and a pair of tuckers and devices connected therewith for imparting thereto both a vertical and an approaching movement for giving to the paper the second fold at either end of the article and for holding the tuckers in such position for an appreciable period, substantially as set forth.

11. In a package - wrapping machine, the combination with a vertically-movable platform, a slide-block, a top-folder and means for actuating the same, of means for delivering an article at a time upon a strip of paper and for periodically feeding forward such strip of paper, a slide-frame and roller, an arm and a horizontally-actuated rod for imparting a back-and-forth movement to the

slide-frame and roller to force the article to be wrapped out upon the vertically-movable platform and simultaneously moving the slide-block out of the way, a slide-plate and roller, an arm and horizontally-actuated rod connected therewith for imparting a back-and-forth movement to the said slide-plate and roller for completing the first fold of the paper around the article and a knife and means for operating the same for simultaneously severing the strip of paper, and a pair of tuckers and devices connected therewith for imparting thereto both a vertical and an approaching movement for giving to the paper the second fold at either end of the article and for holding the tuckers in such position for an appreciable period, and end side-folders in pairs at either side of the machine, and devices connected therewith for imparting thereto simultaneous movements to give to the paper the end folds from each side, substantially as set forth.

12. In a package - wrapping machine, the combination with a vertically-movable platform, a slide-block, a top-folder, and means for actuating the same, of means for delivering an article at a time upon a strip of paper and for periodically feeding forward such strip of paper, a slide-frame and roller, an arm and a horizontally-actuated rod for imparting a back-and-forth movement to the slide-frame and roller to force the article to be wrapped out upon the vertically-movable platform, and simultaneously moving the slide-block out of the way, a slide-plate and roller, an arm and horizontally-actuated rod connected therewith for imparting a back-and-forth movement to the said slide-plate and roller for completing the first fold of the paper around the article and a knife and means for operating the same for simultaneously severing the strip of paper, and a pair of tuckers and devices connected therewith for imparting thereto both a vertical and an approaching movement for giving to the paper the second fold at either end of the article and for holding the tuckers in such position for an appreciable period, and end side-folders in pairs at either side of the machine and devices connected therewith for imparting thereto simultaneous movements to give to the paper the end folds from each side before the tuckers fully release their hold, and end-folders in the form of vertically-placed spring-arms to upturn the folded ends of the paper and so complete the envelop around the article wrapped with the downward movement of the vertically-movable platform, substantially as set forth.

13. In a package - wrapping machine, the combination with a vertically-movable platform and a bracket extension thereto and upright guide parts thereon, of a slide-block 6 and a rod connected therewith; a top-folder 7 above the slide-block and a rod therefor, the said rods passing through the upright parts of the bracket extension, a spring for

bearing the top-folder downward, a guide for the vertically-movable platform and a rocker-arm and cam for operating the same for imparting to said platform the up-and-down movement, substantially as set forth.

14. In a package-wrapping machine, the combination with the vertically-movable platform and a bracket extension thereto, and upright guide parts thereon, of a slide-block 6 10 and a rod connected therewith, a top-folder 7 above the slide-block and a rod therefor, the said rods passing through the upright parts of the bracket extension, a spring for bearing the top-folder downward, a rod connected to the under side of the said platform, a tube fixed in the machine and in which the said rod moves, a slotted frame also connected to the said platform, a rocker-arm *i* pivoted to the machine and having a roller with 20 the free end of the arm in the said slotted frame and a cam for imparting an up-and-down movement to the rocker-arm, the rod and the platform and the parts connected therewith, substantially as set forth.

15. In a package-wrapping machine, the combination with a pair of tuckers 13 and arms to which the same are connected, and a cross-head 42, means at the ends of the cross-head for adjustably holding the rods of the tuckers, cam projections upon the rods of the tuckers and adjustable pins acting thereon and secured to the frame of the machine, a guide for the cross-head, a rocker-arm and means for imparting an up-and-down movement thereto 30 for periodically moving the tuckers and causing them to perform their operations, substantially as set forth.

16. In a package-wrapping machine, the combination with a pair of tuckers 13 and arms 40 to which the same are connected, of a cross-head 42, means at the ends of the cross-head for securely holding the rods of the tuckers, cam projections upon the rods of the tuckers and adjustable pins acting thereon and secured 45 to the frame of the machine, a tube connected to the cross-head and a tube secured in a fixed part of the machine and upon which the cross-head tube slides, a slotted frame connected to the cross-head, a rocker-arm pivoted to a part 50 of the machine and a cam acting upon the roller with the free end of the rocker-arm in the said cross-head to impart a vertical movement to the rocker-arm, the cross-head and the tuckers, substantially as set forth.

17. In a package-wrapping machine and in combination, pairs of end side-folders at either side of the machine, rods connected therewith, parallel shafts in bearings in the base of the machine and through which the rods of the 60 end side-folders pass, toggle-bars connecting the said shafts upon one side of the machine, an arm connected with one shaft and carrying a roller at its free end, and a cam having a slot receiving the said roller, and a means for 65 imparting motion thereto whereby the said pairs of end side-folders are operated simultaneously upon opposite sides of the machine

to fold the paper at the ends from the sides, substantially as set forth.

18. In a package-wrapping machine and in 70 combination, pairs of end side-folders at either side of the machine, rods connected therewith, parallel shafts in bearings in the base of the machine and through which the rods of the end side-folders pass, toggle-bars connecting 75 said shafts upon one side of the machine, an arm connected with one shaft and carrying a roller at its free end and a cam having a slot receiving the said roller and a means for imparting motion thereto whereby said pairs of 80 end side-folders are operated simultaneously upon opposite sides of the machine to fold the paper at the ends from the sides, and means for adjustably connecting the rods carrying the end side-folders to the parallel shafts for 85 regulating their vertical position with reference to the other parts of the machine, substantially as set forth.

19. In a package-wrapping machine, the combination with a vertically-movable platform, a slide-block and top-folder connected therewith, of an arm of suitable form connected to the rod of the slide-block, means for moving the slide-block in one direction with the operations of wrapping the article, 90 and the cam and roller on the cam for acting upon the lower end of said arm and moving the slide-block in the opposite direction, substantially as set forth.

20. In a package-wrapping machine, the 100 combination with a vertically-movable platform, a slide-block and top-folder connected therewith, of an arm of suitable form connected to the rod of the slide-block, means for moving the slide-block in one direction 105 with the operations of wrapping the article and a cam and roller on the cam for acting upon the lower end of said arm and moving the slide-block in the opposite direction, an arm *g* pivoted to the machine and having a 110 bent free end adapted to come in contact with the aforesaid arm on the rod of the slide-block, and devices connected to and acting between the said arm and the power devices of the machine for releasing the said power 115 devices when the machine is not wrapping goods, substantially as set forth.

21. In a package-wrapping machine, the combination with the main shaft, a cam-shaft, a gear upon the main shaft and a loose 120 gear upon the cam-shaft, of a cam connected to the loose gear, a spring-actuated arm *g* pivoted to the frame of the machine and having a bent lower end, a collar secured to the cam-shaft, a dog upon the collar adapted to 125 engage a tooth in a recess of the said cam and devices connected respectively with the collar and with the lower end of said pivoted arm *g* for effecting the prescribed movements of the parts, substantially as set forth.

22. In a package-wrapping machine, the combination with the main shaft, a cam-shaft, a gear upon the main shaft and a loose gear upon the cam-shaft, of a cam connected 130

to the loose gear, a spring-actuated arm *g* pivoted to the frame of the machine and having a bent lower end, a collar having two adjacent peripheral portions of varying outline, 5 projections on the respective peripheries, a dog-spring actuated and pivoted to the said collar and forming a portion of one periphery, projections upon the lower bent end of the said arm *g*, and means for actuating the 10 arm *g* whereby in one position the dog is pressed toward and kept within the peripheral limits of the collar and the projections of the collar and the arm engage, and in the other position the dog is free to move out 15 and engage the tooth of the cam so that the revolving cam through the dog effects the movements of the machine in their progressive order, substantially as set forth.

23. In a package-wrapping machine, the 20 combination with a chute and an arm to which the same is pivotally connected, of a cross-bar secured to the said arm, an oscillating hopper pivoted to the lower end of the chute, a device pivoted to the hopper and located be- 25 tween the hopper and the cross-bar and turning the oscillating hopper in one direction for delivering an article therefrom, and means for returning the oscillating hopper to its normal position, substantially as set forth.

24. In a package-wrapping machine, the 30 combination with a chute and an arm to which the same is pivotally connected, of a cross-bar secured to the said arm, an oscillating hopper pivoted to the lower end of the chute, a device pivoted to the hopper and located be- 35 tween the hopper and the cross-bar and ar- 40 resting the downward movement of articles in the chute during the movement of the oscillating hopper, and means for moving said device out of the path of the articles in the

chute as the hopper is again filled and the operations repeated, substantially as set forth.

25. In a package-wrapping machine and in combination, devices for delivering an article at a time upon and near the free end of a 45 movable strip of paper, devices for progressively moving the article and paper along, devices for folding the free end of the paper around one side, means for moving the article and paper downward, devices for severing the 50 paper strip, devices for lapping the edges of the paper over the article from opposite directions, devices for tucking down the folded parts at the ends, devices for forming the double end folds and other devices for upturning the folded ends, substantially as specified. 55

26. In a package-wrapping machine and in combination, a stationary platform over which a continuous strip of paper is movable, devices for delivering an article at a time upon 60 and near the free end of said strip of paper above said platform, an adjacent vertically-movable platform, devices for moving the article and paper along upon the movable platform and means for folding the free end of 65 the paper around one side, devices for moving the platform with the article and paper downward and devices for severing the paper strip, devices for lapping the edges of the paper over the article from opposite directions, 70 devices for tucking down the folded parts at the ends, devices for forming the double end folds and devices for upturning the folded ends, substantially as specified.

Signed by me this 20th day of February, 75
1901.

JOHANNES TH. PEDERSEN.
